UNITED STATES PATENT OFFICE

PAUL F. COX, OF CHICAGO, ILLINOIS, ASSIGNOR TO GOSS PRINTING PRESS COMPANY,
OF CHICAGO, ILLINOIS, A CORPORATION OF ILLINOIS

RUNNING TYMPAN ATTACHMENT

Application filed May 29, 1930. Serial No. 457,084.

This invention relates to flat bed web printing presses of the type shown for instance in my Patents Nos. 988,548; 1,457,501; 1,475,566 and others. The object of the invention is to provide an attachment for such presses which will prevent smut or offset from the web onto the perfecting impression cylinder, and from it onto the web.

The invention provides a running tympan which is passed around and between the upper or perfecting cylinder and the web, and means for guiding this tympan and feeding it between the perfecting impression cylinder and its contacting bed, in unison with the movement of the web. The invention also provides means for feeding the tympan web from a roll and for re-winding it after use. It also provides means whereby the tympan web may be continuously unwound from the supply roll and continuously re-wound upon the rewinding roll during the operation of the machine, and for intermittently stopping and shifting the portion of the tympan web which contacts with the web in the press in accordance with the intermittent shifting of the web between the beds and cylinders.

While the invention is primarily designed for use in flat bed web perfecting presses of the character set forth it is applicable to other types of machines in which traveling cylinders are employed or in which the printing mechanism is "thrown off impression" during the feeding of the web or sheet, or on one stroke and "thrown on impression" during the printing or the return stroke.

I will explain one practical embodiment of the invention with reference to the accompanying drawing to facilitate an understanding of the invention by those skilled in the art. In the claims the essentials of the invention, and the novel features of construction and novel combinations of parts for which protection is desired, are summarized.

The drawing is a diagrammatic side elevation of a web printing press and novel attachment for operating the running tympan.

The type of press shown in the drawing has parallel type beds 1, 1a arranged one over the other in a suitable main frame.

Cooperating with these beds are traveling impression cylinders 2 and 2a, which are mounted in bearings in crossheads 3 which are guided in longitudinal guideways in the sides of the press frame, and are reciprocated longitudinally of the press, so as to move the cylinders 2 and 2a back and forth over the beds, by means of pitmen 3a connecting the crossheads with crank gears (not shown) which may be operated by any suitable mechanism. The cylinders can be thrown "on impression" during one stroke, and thrown "off impression" during the other stroke of the crossheads. The general construction and arrangement of the aforesaid parts and the operation thereof are well known, and may be as shown and described in my aforesaid patents; and therefore need no further detailed illustration or explanation herein.

The web w may be led from a web roll, not shown, over a guide g2 to a looping roller 6a on a lever 6 then inward over the bed 1a to and over a guide roller g3 mounted on the crossheads adjacent cylinder 2 and thence up over a guide roller g4 mounted on the crossheads beside cylinder 2; thence out over a stationary guide g5, mounted on the rear end of the frame; thence up over a guide g6 mounted on the frame; thence inwardly to and over a roll g7 mounted on the crossheads adjacent cylinder 2a; thence down under cylinder 2a and up over a guide g8 mounted on the crossheads beside cylinder 2a; thence forward to and around a looping roller 6b mounted on the upper ends of the arms 6; thence back under a guide roller g9; thence to the delivery as in Patent No. 1,475,566.

When the cylinders are on impression and moving across the beds 1, 1a, the web is stopped between the rollers g2 and g9 by the action of the looping rollers 6a, 6b which move in opposite directions, one giving out web as required by the delivery, and the other taking up the web fed in by the feed rolls, as required by the continuous infeed and out-feed of the web. While the cylinders are off impression the web is shifted forward by the combined action of the looping rollers in giving out and taking up web, and the con-

tinuous action of the outfeed and delivery mechanisms, in a manner well understood in the art and which needs no detailed explanation herein.

- 5 The first printed side of the web comes into contact with the surface of the impression cylinder $2a$ and part of the fresh ink on the cylinder $2a$ and web will adhere to the surface of the cylinder and "smut" the same, and the smut is 10 pressed by the cylinder onto the web passing thereunder producing "offset" on the web, and spoiling the appearance of the printed sheet.

To prevent such smutting I employ a tympan web t which is preferably arranged and 15 operated as follows. The roll T of tympan paper, or other suitable material, may be mounted on a shaft $15a$ which is removably mounted on a frame F adjacent the end of the press frame, as shown in Fig. 1. The 20 tympan t is led from the roll T to and over a guide G up and over a roller 9 which is journaled in vertically movable bars 11 in frame F and then passes down under a guide G' to and over a guide $G2$ mounted on the cross 25 heads adjacent the cylinder $2a$ and above the web guide $g7$; then between the cylinder $2a$ and the bed $1a$, then up over a guide $G3$ on the crossheads adjacent guide $g8$; then the 30 tympan is led to a guide $G4$ on the press frame, up over a guide $G5$ on the press frame and back to a guide $G6$ on the frame F above the guide G' ; then down under a roller $9a$, similar to roller 9 and journaled in the bars 11 , parallel with and above the roller 9 , then the 35 tympan passes up over a guide $G7$ and down to a rewinding roll R whose shaft 8 is guided in vertical slots in the sides of frame F . Roll R rests upon two parallel rolls $7-7$ as shown whose shafts $7a$ are journaled in the sides of 40 frame F . Shafts $7a$ carry gears $7b$ which respectively mesh with a gear $5a$ on a shaft 5 and a beveled gear $5b$ on shaft 5 meshes with a beveled gear $4a$ on the upper end of a vertically disposed shaft 4 journaled in suitable 45 bearings attached to frame F , and the lower end of shaft 4 has a beveled gear $4b$ meshing with a beveled gear $13a$ on a counter shaft 13 journaled in suitable bearings in the frame F and extending across to the press 50 frame. Shaft 13 may be geared by suitable gearing, indicated at $13c, 13d, 13e$, not shown, to the main drive shaft S of the press, so that the periphery of drums 7 will be driven in exact accordance with the peripheral speed of 55 the web feeding and web charging rolls of the press.

The bars 11 may be guided in vertical movements by any suitable means. As shown the journals $9b$ of roller $9a$ extend into vertical 60 guide slots $9s$ in the sides of frame F . The bars 11 are connected to arms $11a$ on a shaft 12 ; to which shaft is attached a lever $12a$ having a roller $12b$ engaging a cam $7s$ on the shaft of the adjacent drum 7 . The cam $7s$ is 65 so shaped that it will cause lever $12a$ to move

bars 11 up and down at the proper times and to the proper extent to cause the tympan looping rollers $9, 9a$ to shift the tympan web t over the bed $1a$, and between the cylinder $2a$ and bed $1a$, in exactly the same manner and 70 at the same time that the web w is shifted over such bed, and between said bed $1a$ and the cylinder $2a$.

The rewinding roll R is rotated by frictional contact with rolls 7 at the same peripheral speed as said rolls, and these, as stated, are driven by the gearing at the same peripheral speed that the web feeding and delivering rolls are driven in the press. The tympan equalizing rollers $9, 9a$ are operated 80 once for each reciprocation of the cylinders over the bed; like and in time with the operation of the web looping rollers $6a, 6b$. The cam $7s$ is so shaped that the movement of the tympan web t will correspond with the movement of the web w in the press at all times.

The shafts 4 and 13 and their gearing, and the gears driving the rollers 7 , can be mounted outside or inside of the frame work as desired. The cam $7s$, the lever $12a$, and the bars 11 are preferably mounted inside of the frame work.

When the tympan web has been practically exhausted from the roll T and rewound in the roll R , the press can be stopped and the 95 rewound roll R substituted for the roll T , and the latter roll substituted for the roll R , then the tympan is rethreaded through the press as above described.

I claim:

1. Tympan web handling mechanism; for use on traveling cylinder web printing presses wherein a portion of the web is stopped during the taking of an impression and then forwarded more rapidly; comprising a tympan supply roll, a pair of tympan rewinding rolls mounted in a frame adjacent one end of the press, reciprocable bars mounted in said frame, a pair of looping rollers mounted in said bars, a pivoted lever for operating said bars, a cam connected with one of the rewinding rolls for operating said lever, and guides for directing the tympan from said supply roll to and over one of said looping rollers thence to and between the 110 press cylinder and the web to prevent offset on the cylinder, thence back to and over the other looping roller and to the rewinding roll; with means for operating the said rewinding rolls and the cam actuating the looping rollers to intermittently shift the tympan past the cylinder.

2. Tympan handling devices; for use on traveling web printing presses wherein a portion of the web is stopped during the taking of an impression and then forwarded more rapidly; comprising a tympan supporting roll mounted in a frame spaced from one end of the press, a pair of tympan rewinding rolls mounted in said frame, reciprocable bars 125

mounted in said frame, a pair of looping rollers mounted on said bars, a cam on the shaft of one tympan rewinding roll, a lever controlled by said cam and operating the said bars, and guides for directing the tympan from said supply roll to and over one of the looping rollers thence to and between the cylinder and web back to and over the other looping roller to the rewinding rolls; with means for driving the rewinding rolls and cam from the press, whereby the tympan is shifted past the cylinder simultaneously with the web.

3. Tympan web handling mechanism; for use on traveling web printing presses wherein a portion of the web is stopped during the taking of an impression and then forwarded more rapidly; comprising a frame adjacent one end of the press, a tympan supply roll and a pair of tympan rewinding rolls mounted in said frame, a reciprocable support mounted in said frame, a pair of looping rollers carried by said support, a lever for operating the support, a cam attached to the shaft of one of the rewinding rolls and operating said lever, and guides for directing the tympan from said supply roll to and over one looping roller thence to and between the cylinder and the web to prevent offset on the cylinder, and thence back to and over the other looping roller to the tympan rewinding rolls; with gearing between a driven member of the press and the tympan rewinding rolls whereby the tympan handling mechanism is operated to intermittently shift the tympan past the cylinder simultaneously with the web.
